DESIGN FOR A TRAFFIC SIGNAL

Martin Hauser, Kansas City, Kans.

Application December 13, 1940, Serial No. 97,288

Term of patent 7 years

To all whom it may concern:

Be it known that I, Martin Hauser, a citizen of the United States, residing at Kansas City, in the county of Wyandotte and State of Kansas, have invented a new, original, and ornamental Design for a Traffic Signal, of which the following is a specification, reference being had to the accompanying drawing, forming part thereof.

In the drawing:

Fig. 1 is a perspective view of a traffic signal showing my new design.

Fig. 2 is a front elevational view thereof.

Fig. 3 is a side elevational view thereof.

Fig. 4 is a plan view thereof.

The broken lines across the lower ends of the support shown in Figs. 1, 2 and 3 indicate indeterminate length.

I claim:

The ornamental design for a traffic signal, as shown and described.

MARTIN HAUSER,
